POST MOUNTED INSULATING SUPPORT FOR ELECTRIC FENCE WIRE

David A. Epp, Henderson, Nebr., assignor to Henderson
Manufacturing Co., Inc., a corporation of Nebraska

Filed Mar. 31, 1967, Ser. No. 6,458

Term of patent 14 years

(Cl. D26—10)

Fig. 1.

Fig. 2.

Fig. 3.

Fig. 4.

Fig. 5.

FIG. 1 is a front and upper perspective view of a post-mounted insulating support for electric fence wire, showing my new design;

FIG. 2 is a bottom plan view;

FIG. 3 is a front elevational view;

FIG. 4 is a side elevational view taken from the left hand side of FIG. 3, the other side being substantially the same; and

FIG. 5 is a rear elevational view.

The fragmentary portion of a post is shown in broken lines in FIG. 1 for illustrative purposes only.

I claim:

The ornamental design for a post mounted insulating support for electric fence wire, as shown and described.
